UNITED STATES PATENT OFFICE.

WILLIAM S. PACA, OF ERIE, PENNSYLVANIA.

TELEPHONE-TOLL SLOT-MACHINE.

SPECIFICATION forming part of Letters Patent No. 728,964, dated May 26, 1903.

Application filed August 26, 1902. Serial No. 121,026. (No model.)

To all whom it may concern:

Be it known that I, WILLIAM S. PACA, a citizen of the United States, residing at Erie, in the county of Erie and State of Pennsylvania, have invented certain new and useful Improvements in Telephone-Toll Slot-Machines; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

My invention relates to improvements in telephone-toll slot-machines, and has for its object the production of a slot mechanism which will accurately signal the insertion therein of coins of different values and at the same time fail to operate and signal when mutilated coins or blank disks of metal either smaller, thicker, or thinner than current coins are inserted therein.

Another object attained is the prevention of the clogging and disabling of the mechanism by the insertion of mutilated coins or metal disks therein of imperfect size or thickness.

I accomplish these results by means of the construction and arrangement of mechanism hereinafter set forth and described, and illustrated in the accompanying drawings, in which—

Figure 1 is a top or plan view of a telephone-toll slot-machine embodying my invention. Fig. 2 is a corner view of the same in elevation with portions of the sides and the lower end thereof broken away. Fig. 3 is a view in perspective of the plates, hereinafter designated as 1 2 3, comprising the slot mechanism of my machine separated from each other. Fig. 4 is a view of the under surface of plate 1. Fig. 5 is a plan view of plate 2. Fig. 6 is a plan view of plate 3. Fig. 7 is a view of the under surface of my machine with portions of the box broken away. Fig. 8 is a diagrammatic section of the mechanism on the line $x-x$ in Fig. 1. Fig. 9 is an enlarged detail view of the ratchet mechanism of the machine. Fig. 10 is a side view of the same with the mechanism in the position shown in Fig. 9 and with the plates 1, 2, and 3 in sec-

tion on the line $y-y$ looking in the direction of the arrow w . Fig. 11 is a side view of the same with the mechanism in the position 55 shown in dotted lines in Fig. 9 and with the plates in section, as in Fig. 10, looking in the direction of the arrow z .

In the drawings illustrating my invention, A is a box inclosing the mechanism of my invention. Upon the top of this box A, I secure an inner plate 3 and an outer or top plate 1, and between these plates I mount a plate 2 upon a shaft B, journaled in the plates 1 and 3 and provided with a crank B' on its upper 65 end, as illustrated in Figs. 2, 3, 10, and 11.

Upon the lower end of the shaft B, I secure a retracting-spring C, one end of which is secured to a stud c in the plate 3. Upon the shaft B below the spring C there is secured 7c a ratchet-wheel D, provided with a spring-actuated ratchet D', secured to a stud d in the plate 3. Upon the ratchet-wheel D there is a spring-actuated deflecting-strip d', over which the point of the dog D' travels during the reverse movement of the shaft B and ratchet-wheel D. The object of this mechanism is to prevent the backward movement of the shaft B before it has completed its full forward traverse, which traverse is limited by means 75 of the upright studs $b-b'$ in the plate 1.

In the top of plate 1 there are coin-receiving holes made of the proper size to receive coins of each denomination to be used in the machine. In the drawings I have shown 85 holes E E' E'', designed to receive quarters, nickels, and dimes. However, any number of holes can be utilized as desired. In the under surface of plate 1 from the hole E there is a curved depression F to allow the collar 90 around the opening H in the rotating plate 2 to travel, this opening H in the collar and plate 2 being the exact depth of the thickness of a quarter, and in the under surface of the plate 1 from the hole E' there is also a curved 95 depression F' of just sufficient depth to allow the collar around the opening H' in the rotating plate 2 to travel, this opening H' in the collar and plate 2 being of the exact depth of the thickness of a nickel, while 100 from the hole E'' there is no depression in the under surface of plate 1, as the thickness of the plate 2 at the opening H'' therein is exactly the thickness of a dime. In the plate 3

- I make openings I, I', and I², adapted to register with the openings H, H', and H² in the plate 2 at the termination of its forward traverse, these openings being just sufficient to permit a quarter, a nickel, and a dime, respectively, to drop out. In front of each of these openings in the line of travel of the openings H, H', and H² in the plate 3 I make oval openings J, J', J², so that coins smaller in diameter than the standard sizes designated to be deposited in the openings E, E', and E² will when carried around by the rotation of the plate 2 fall through the openings J, J', and J² before reaching the proper discharge-openings I, I', and I² without operating the signal-bell mechanism, herein-after described. To facilitate the discharge of the coins from the openings I, I', and I² in the plate 3, I provide upturned springs LL', L², which extend upward through the slots i, i', i² in the edges of the openings I, I', I² into radial slots h, h', h² in the rotating plate 2 and operate to force the coins downward as they come into contact therewith over the openings I, I', I², this feature being clearly illustrated in Fig. 8. To the under surface of plate 3 I secure standards K, K', K², to which bells k, k', k² are secured, each of different tone, so that the ring of each bell gives a different signal, as illustrated in Figs. 2, 7, and 8, and on the plate 3 between the openings I, J, I', J', and I², J² therein I secure ears m, in which spring-actuated bell-hammers M, M', M² are pivoted, the heels of which bell-hammers extend through openings l, l', l² in the plate 3 into the radial grooves h, h', h² in the plate 2, as shown in Fig. 8, so that when a coin is moved around to either of the discharge-openings I, I', I² it contacts with the heel of one of the bell-hammers M, M', M², and during its passage to the discharge-opening operates the bell-hammer, so as to cause it to strike the bell and sound the appropriate signal.
- In operation when the proper-sized coin is inserted into one of the openings in the plate 1 and the crank B' moved in the direction of the arrow until it contacts with the stop b', the plate 2 is thereby rotated until the coin passes out of the proper discharge-opening in the plate 3. The crank B' being then released it is automatically moved back to the stop b by means of the spring C, the dog D' meanwhile passing over the deflecting-strip d' during the backward movement of the crank B'. If, however, the crank B is moved forward a quarter or more of its traverse, the dog D' operates to prevent its being returned to its normal position before its traverse has been completed.
- In case a coin which has been mutilated until it is out of shape is deposited in one of the openings in the plate 1 it will not enter the opening, and in case a disk of metal of the proper diameter but thicker than the proper coin is deposited therein the crank B' cannot be moved forward, and it must be removed before the mechanism will operate.

If the disk deposited is of smaller diameter than the coin, during its traverse it will drop through the oval discharge-opening in the plate 2 without contacting with the bell-hammer. If, however, a disk is inserted of the proper diameter but thinner than the normal thickness of the proper-sized coin, it will pass over the oval opening and under the heel of the bell-hammer and out at the proper discharge-opening in the plate 3 without operating the bell-hammer and ringing a signal.

I have thus shown and described a convenient mechanism for utilizing my invention. I am aware, however, that modifications can be made therein without departing from the spirit of my invention.

Therefore what I claim as new, and desire to secure by Letters Patent of the United States, is—

1. In a telephone-toll slot mechanism, a stationary top plate having different-sized circular openings therein, and recesses in its under surface communicating with some of said openings, a movable plate immediately below the top plate, having circular openings therein corresponding in their diameters with the diameters of the openings in the top plate, annular projections of different heights on the top of the movable plate around some of said openings therein extending upward into the recesses in the lower surface of the top plate, a stationary bottom plate having discharge-openings therein corresponding in their diameters with the diameters of the openings in the other plates, and means for moving said intermediate plate, substantially as set forth.

2. In a telephone-toll slot mechanism, a stationary top plate having different-sized coin-receiving circular openings therein, and recesses of different depths in its under surface communicating with some of said openings, a movable plate immediately under and in contact with the under surface of said top plate having openings therein corresponding in their diameters with the diameters of the openings in the top plates, annular collars of different heights on the movable plate around some of the openings therein extending up into the recesses in the lower surface of the top plate, and slots therein extending from said openings, a stationary bottom plate having circular discharge-openings therein corresponding in their diameters with the openings in the other plates, and also oval auxiliary discharge-openings of less diameter transversely to the line of travel of the movable plates, than the regular discharge-openings, spring mechanism at the edges of the regular discharge-openings in the lower plate extending up into the slots in the movable plate and means for moving the movable plate, substantially as and for the purpose set forth.

3. The combination in a telephone-toll slot-machine, of a box, a stationary top plate thereon having openings therein for different-

sized coins and recesses in its under surface, another stationary plate below the top plate, having corresponding discharge-openings therein for different-sized coins, and other 5 narrower openings for discharging undersized coins, a rotary plate between said upper and lower plates, openings in said plate corresponding to the openings in the upper plate, collars around some of the openings in 10 the intermediate plate adapting them to receive coins of different thicknesses, and annular slots leading from said openings, crank, spring, ratchet, and stop mechanism for con-

trolling the movement of the intermediate plate, a different-toned signal-bell at each 15 normal-sized discharge-opening in the lower plate, and bell-hammer mechanism for each bell adapted to be actuated by the passage of the proper-sized coin, substantially as and for the purpose set forth.

20 In testimony whereof I affix my signature in presence of two witnesses.
